UNITED STATES PATENT OFFICE.

ALEXANDER BOLLI AND LAWRENCE LICHTINGER, OF SEATTLE, WASHINGTON.

COIN-CONTROLLED STAMP-SELLER.

1,010,577.

Specification of Letters Patent.

Patented Dec. 5, 1911.

Application filed February 13, 1911. Serial No. 608,355.

To all whom it may concern:

Be it known that we, ALEXANDER BOLLI and LAWRENCE LICHTINGER, citizen of the Swiss Republic and subject of the Emperor of Germany, respectively, residing at Seattle, in the county of King and State of Washington, have invented certain new and useful Improvements in Coin-Controlled Stamp-Sellers, of which the following is 10 a specification.

This invention relates to that class of vending machines in which an inserted coin temporarily serves to render the machine operable for the delivery of the vended 15 article.

The object of the invention is the provision of a simple and efficient machine of this character which is particularly adapted for the sale of postage stamps.

20 The invention consists in the novel construction and combination of devices, as will be hereinafter described and claimed.

In the accompanying drawings, Figure 1 is a front elevation of devices embodying 25 our invention, with the containing case shown partly in cross section. Fig. 2 is a longitudinal section through 2—2 of Fig. 1. Figs. 3 and 4 are side elevational views taken from the right and left hand sides of 30 the machine.

The reference numerals 5 and 6 designate the side members of a frame rigidly secured to a base member 7. Adjacent to the rear end of said frame and journaled in 35 bearings provided therein is a transversely arranged arbor 8 for a spool 9 whereupon is wound printed paper 10 constituting a strip of postage-stamps comprised of a number of longitudinal rows, as five, for 40 example. At a distance in front of the spool is a series of guide rolls 11, 12 and 13 whose conjoint office is to lead the end of the aforesaid strip into the interstice between a pair of feed rolls 14 and 15 which are located 45 near the front end of the frame and arranged to deliver the strip over the edge 16 of a shear-plate 17 which is rigidly secured to said frame members. Intermediate the rolls 12 and 13 the frame supports a 50 transverse bar 18 to which is secured a plurality of knife blades 19 spaced apart equal to the widths of the various rows of stamps upon said strip and, as the latter is progressively advanced through the instrumentality 55 of said feed rolls, incisions are made thereby between the several rows of stamps.

Fulcrumed by a pivotal screw 20 to the front end of the frame member 5 is a lever whereof one of its arms, 21, is sharpened along its lower edge to serve as a movable shear-blade, complementary to the shear-plate 17; while the other arm 22 carries a roller 23 which tracks upon the periphery of a cam 24 through the agency of a spring 25 tending to tilt the blade arm 21 upwardly. 60 26 is a roller carried by said blade arm to coöperate with a guide bar 27 for maintaining the cutting edge of the blade arm in juxtaposition with the edge 16 of plate 17. Extending transversely through said frame 65 members and journaled in bearings therein provided is a shaft 28. Keyed or otherwise secured for rotary movement with this shaft is the above mentioned cam, a ratchet wheel 29, and an arm 30. The latter is employed to engage the successively presented 70 fingers 31 which extend radially from a hub 32 upon the axle 15' of the feed roll 15 to afford intermittent rotary motion thereto sufficient to advance the stamp-strip the 75 length of a stamp in each rotation of the shaft. Said cam is formed with its periphery extending in a spiral curve from its minimum radius to the beak 24', as indicated in Fig. 3. Loosely mounted on the 80 shaft is a vibratory bar 33 serving as a carrier for a detent 34 for said ratchet wheel at one end and a pawl 35 at the other end. This pawl has its free end directed rearwardly and is supported upon a ledge 36 85 of a standard 37 secured to or made integral with the machine frame. Said ledge is located at the forward part of the standard and terminates at a wall or stop 38. Said standard is provided at its upper end with 90 a recess 39 of a depth measured from the top of the stop 38 slightly less than the diameter of the coin with which the machine is intended to be operated, as a one-cent piece. The coin is placed within a slot 40 in the 95 case and is transmitted and deposited in the recess 39 between the stop 38 and the pawl 35 by means of a chute 41, Fig. 3.

42 represents a pull rod attached to the carrier 33 and extending through an opening in the case for actuating said carrier in opposition to a helical spring 43. In proximity to the bottom of the casing is an opening 46 through which the stamps are removed from a trough 47 into which they 100 fall after being sheared from the various strips.

The operation is as follows: When a coin is inserted in the machine it falls into the depression 39 of standard 37 to occupy the position in which it is denoted by C in Fig. 3. With the coin thus lodged, the depositor then pulls the rod outwardly resulting in the carrier 33 being vibrated to afford a rotary movement to the ratchet wheel 29 through the agency of the detent 34. In such movement of the carrier, the pawl 35 is thrust rearward and is tilted upwardly by the coin so as to pass freely over the stop 38. When the ratchet wheel is turned the shaft 28 to which it is secured is also similarly affected together with the cam 24 and the arm 30. The cam in its turning pushes the lever arm 22 upwardly thereby causing the shear blade 21 being swung downwardly to an extent sufficient to accomplish the cutting off of a single stamp from one of the rows of stamps which are protruded in front of the shear plate 17. A stamp when thus severed falls into the trough 47 for removal. Upon the release of the rod 42 the spring 43 asserts itself to restore the carrier to the normal position in which it is represented in Fig. 3; whereupon the detent 34 is in position for engagement with another tooth of the ratchet wheel and the pawl 35 has been dragged back over the coin into the position in which it is shown in the view. In being thus dragged back, the pawl being on the circumference of the coin will roll the latter out of an opening provided at the front of the standard to drop into a coin receptacle 44 below.

If a coin is absent from the recess 39, it is obvious that the pawl will encounter the stop 38 to interrupt the travel of the pawl 40 and thus make the carrier and the detent 45 inoperative. After a succession of such operations all of the stamps protruding beyond the shear members 17 and 21 will have been cut off and upon the occurrence of which the cam will have its beak carried beyond the roll 23 when the spring 25 will exert its power and tilt the blade 21 upwardly. In the early portion of the next rotary motion of the shaft, the arm 30 engages one of the fingers 31, see Figs. 1 and 4, to revolvably move the same to turn the feed roll 15 sufficient to advance the stamp strip the length of a stamp outside of the cutting plane of the shear members. The stamp strip in being moved is ripped, so to speak, by the knives 19 to divide the strip into rows of stamps as previously explained.

What we claim is—

1. In a vending machine, the combination with a supporting frame, normally inoperative means for the delivery of a vended article, a shaft journaled in the frame, a sta-

tionary shear knife carried by the frame, a movable shear knife pivoted intermediate its ends to the frame to provide a relatively long and a relatively short arm, the long arm having a knife edge coacting with the shear plate, a guide carried by the frame and a roller carried by the long arm of said knife to engage said guide, a cam carried by the rotary shaft to engage the short arm of said knife, a ratchet wheel mounted for rotation with said shaft, a carrier, a detent on the carrier for engagement with the ratchet wheel, a pawl carried by the carrier, a stop for arresting the travel of said pawl, a pull rod connected with the carrier, and a spring for returning the carrier to initial position after a complete stroke of the movable knife.

2. In a vending machine, the combination with normally inoperative means for the delivery of a vended article, of severing means therefor comprising a rotary shaft, a shear plate and a pivoted knife, the knife being pivoted intermediate its ends to provide a relatively long and relatively short arm, means for guiding the outer end of the knife to insure coaction of the knife with the shear plate, a cam on the shaft for engagement with the relatively short arm of the knife, a ratchet wheel mounted for rotation with the shaft, a carrier, a detent on the carrier for engagement with the ratchet wheel, a pawl carried by the carrier, a stop for arresting the travel of said pawl, means for returning the pivoted knife to initial position after a complete revolution of the cam, and means actuated by the shaft for operating the normally inoperative vending means.

3. In a vending machine, the combination with normally inoperative means for the delivery of a vended article, of a stationary shear plate, a cutting knife coacting therewith, said knife pivoted intermediate its ends to provide a relatively long and a relatively short arm, means for actuating the outer end of the long arm of the knife to insure coacting movement thereof with the shear plate, a rotary shaft, a cam on the shaft engaging the relative short arm of the cutting knife, a ratchet wheel mounted for rotation with the shaft, a carrier, a detent on the carrier for engagement with the ratchet wheel, a pull rod connected to the carrier, and means for returning the carrier and cam to initial position after the cam has made a complete revolution.
